(57) **CLAIM**

The ornamental design for a ring, as shown and described.

DESCRIPTION

FIG. 1 is a perspective view showing the front, bottom and left sides of my ring design.

FIG. 2 is a perspective view showing the bottom and rear sides of my ring design.

FIG. 3 is a top view of my ring design.

FIG. 4 is a bottom view of my ring design.

FIG. 5 is a perspective view showing the bottom and right sides of my ring design.

FIG. 6 is a perspective view showing the top and right sides of my ring design; and,

FIG. 7 is a perspective view showing the front and top sides of my ring design.

The broken lines shown in the drawings illustrate portions of the ring that form no part of the claimed design.
